UNITED STATES PATENT OFFICE.

CHARLES T. PAYNE, OF GRAND RAPIDS, MICHIGAN.

METHOD OF MAKING MINIATURE LOG HOUSE.

Application filed April 28, 1928. Serial No. 273,499.

This invention relates to toy or miniature houses which simulate the appearance of log houses, and which are suitable for birds, etc.

The main objects of this invention are to provide an improved construction of miniature log house which will be substantial and rigid in construction, and to provide an improved method of arranging the twigs on substantial backing members so that when the ends of the members are abutted at right angles, projecting ends of alternate twigs will be in dovetailed relationship.

An illustrative embodiment of this invention is shown in the accompanying drawings, in which:

Fig. 1 is a view in perspective of a complete miniature log house having a detachable floor shown in spaced relation to the house.

Fig. 2 is a top plan view of a jig for holding the parts from which the side and end walls of the house are made.

Fig. 3 is a sectional view taken on the line 3—3 of Fig. 2.

Fig. 4 is a view in perspective, taken in mid-section, of the jig which holds the parts for making the roof of the house.

Fig. 5 is a view in front elevation of an end wall of the house as constructed in the jig shown in Fig. 2.

Fig. 6 is a view in front elevation of a side wall of the house as constructed in the jig shown in Fig. 2.

In the construction shown in the drawings, a jig is provided for holding the parts from which the side and end walls are made, and comprises a base plate 1 having a metal face 2 on the top side thereof.

A cleat or step 3 is secured by screws 4 to the face of the jig adjacent and parallel to one longitudinal edge. Transverse cleats 5, 6 and 7 are also similarly secured to the face of the jig, at right angles to the cleat 3 and abutting thereagainst.

The cleats 5, 6 and 7 are provided with inwardly extending base flanges 8, 9 and 10 respectively which are of substantially the same thickness as backing members or boards 11 and 12 which are used in the end and side walls respectively of the device.

An upstanding cleat 13 having an inwardly extending toe 14 is also provided at the medial point of the backing board 12 at the side thereof opposite to the cleat 3.

In constructing a side wall with the use of this jig, the backing board 12 is first placed

in position between the flanges 9 and 10 by inserting one edge under the toe 14 and then lowering the other side until the board rests upon the metal face plate 2.

A series of twigs 15, all cut to the same length, are then placed on the board. The first twig adjacent to the cleat 13 is placed in position first by slipping it under the toe 14 and with its left end resting upon the flange 9 and abutting against the cleat 6. The twigs are of a length so that when an end thereof abuts against either the cleat 6 or 7, the opposite end thereof will be substantially flush with the opposite end of the backing board 12. The next twig is then placed against the first with its right end resting upon the flange 10 and abutting against the cleat 7. Successive twigs are likewise placed in position in staggered relationship until the last twig lays along and contacts with the cleat 3.

Small nails 16 are then driven through each of the twigs 15, one adjacent each end thereof, and the nails are of sufficient length so as to pass through the board 12 and come in contact with the metal face plate 2 which clinches the ends as shown in Fig. 3.

The backing board 12 with the twigs nailed thereto, is then removed from the jig by first raising the edge next to the cleat 3 and then shifting slightly in the direction of said cleat so as to withdraw the opposite edge thereof from under the toe 14 of cleat 13. The side wall as thus formed is shown in Fig. 6 of the drawings.

The end walls for the miniature house are formed in much the same manner except that the backing board 11, at the edge opposite to the edge abutting against the cleat 3, is of inverted V shape and the twigs nailed thereto are trimmed off flush with each side of the board to form the gable of the house as shown in Fig. 5 of the drawings.

The two sides of the roof of the house are of the same construction and are made on the jig shown in Fig. 4 of the drawings. This jig comprises a base 17 having a metal face plate 18 and cleats 19 and 20 adjacent the opposite ends thereof. The cleat 19 is of inverted L shape with the flange 19A extending inwardly.

The underside of the inwardly extending flange 20 is provided with a depending strip 21 of yielding material such as rubber and is secured to the flange by a thin flexible metal

strap 22, which extends longitudinally along the underside of the strip and has its opposite ends wrapped up around the flange 19^A and secured to the top side thereof by screws 5 or the like.

The cleat 20 is of the same construction, having a yieldable strip 23 held by a strap 24, but with the addition of an inwardly extending base flange 25.

- 10 The far side of this jig is also provided with a cleat 26 having an inwardly extending toe in the same manner as the cleat 13. In this jig the backing board or member 27 is slipped in edgewise until it abuts against 15 the cleat 26.

Twigs 28, all cut to uniform standard length, are then slipped in with the opposite ends thereof abutting against the cleats 19 and 20, and being held yieldingly down 20 against the board 27 by the strips 21 and 23.

It will be noted that the twigs 28 are as much longer than the board 27, as the base flange 25 is wide, so that when the roof is applied to the house, the protruding ends 25 of the twigs will form the eaves.

The twigs 28 are secured to the backing member 27 by nails 29 in the same manner as shown in Fig. 3, and then the board 27 with its twigs nailed thereto is slid out of 30 the jig in an edgewise direction.

In assembling a miniature house from these three jig formed units, the backing boards of two end units and two side wall units are arranged at right angles to each other and 35 secured together. The staggering of the twigs is so arranged that the protruding ends of one wall fit between the protruding ends of the adjacent walls in much the same manner as in the building of a log cabin.

- 40 The roof members are then nailed in place with the protruding ends of the twigs forming the eaves along the sides of the house. A floor plate 29 may be detachably secured to the house for convenience in cleaning, and

one end wall is provided with an opening 30 45 to permit ingress and egress of the birds.

A forked twig 31 may be nailed to the end wall that has the hole 30 therein, with one arm 32 of the twig positioned in spaced relation to the plane of the wall so that a bird 50 can alight thereon.

Although but one specific embodiment of this invention has been herein shown and described, it will be understood that numerous details of the construction shown may be altered or omitted without departing from the spirit of this invention as defined by the following claims.

I claim:

1. The method of making a device of the 60 class described comprising the placing of a backing member in a jig, arranging a series of twigs of substantially the same length in parallel relationship, the opposite ends of alternate twigs being substantially flush with the opposite ends of said backing member, and the other ends of said twigs protruding beyond the ends of said backing member, securing said twigs to said backing member and then removing said member and twigs 70 from said jig.

2. A device of the class described comprising a plurality of backing members arranged end to end at right angles to each other to form side walls, twigs secured to said backing members with one end of each twig substantially flush with one end of its backing member, and the other end thereof protruding beyond the other end of said backing member, said twigs and backing member being positioned so that the protruding ends of said twigs of one backing member fit between the protruding ends of the twigs on the adjacent backing member.

In testimony whereof I have hereunto set 85 my hand at Grand Rapids, Michigan, this 25th day of April, 1928.

CHARLES T. PAYNE.
